UNITED STATES PATENT OFFICE.

ELBERT R. O'KEEFFE, OF OMAHA, NEBRASKA, ASSIGNOR OF ONE ONE-HUNDREDTH TO
ARTHUR H. STURGES, OF OMAHA, NEBRASKA.

MAGNETIC RECIPROCATOR FOR ELECTRIC GENERATORS.

1,215,401.

Specification of Letters Patent.

Patented Feb. 13, 1917.

Application filed October 13, 1915. Serial No. 55,635.

To all whom it may concern:

Be it known that I, ELBERT R. O'KEEFFE, citizen of the United States, residing at Omaha, in the county of Douglas and State 5 of Nebraska, have invented certain new and useful Improvements in Magnetic Reciprocators for Electric Generators, of which the following is a specification.

This invention relates to improvements in 10 magnetic reciprocators for electric generators, of the class providing means for longitudinal reciprocation of the commutator and its shaft, to permit uniformity in the wear of the surface of the commutator from the 15 contacting brushes. The invention has for its principal object to provide means to control the longitudinal movements of the parts mentioned which will be effective in operation and will consist of such parts that they 20 will be comparatively inexpensive in production, and that vibration, during operation, will be practically eliminated.

The novel construction, combination and arrangement of parts employed are illustrated 25 in the accompanying drawings and pointed out in the appended claims, and the operation of the preferred construction shown will be fully described herein.

In the drawing, Figure 1 is a plan view 30 of an electric generator, the housing for the armature and coils, and the housings for the shaft and electromagnets being broken away.

Figs. 2 and 3 are enlarged details relating 35 to Fig. 1 to clearly illustrate the electrical actuating mechanism employed. Fig. 2 is a plan view showing a plurality of electromagnets and their connections, the bearings for the shaft being in transverse section. Fig. 3 is a view similar to that shown 40 in Fig. 2, the electromagnets and part of the shaft being in longitudinal section, as on line 3 3 of Fig. 4.

Fig. 4 is an end view of the parts shown 45 in Fig. 2. Fig. 5 is a view looking to the ends of the electromagnets, as a section on line 5 5 of Fig. 2, to show the arrangement of the electrical conductors, and relative position of parts.

50 It will be understood that in the use of electric generators, as usually constructed, a continued contact and resulting wear of the metallic brushes upon the soft metal of a commutator tends to produce scratches, 55 grooves and abrasions upon the peripheral

surface of the copper plates, the resulting objectionable features being that the plates will soon become injured; also when the generator is employed in connection with the storage batteries of telephone systems, 60 the vibration produced by the scratching and sparking causes sound waves to be conducted through the storage batteries and service conductors, the "buzzing" sounds tending to produce confusion and inconvenience 65 when using telephones. Also it is obvious that uniformity in the flow of the electrical current is desirable when an electric generator is used for providing electrical energy for lighting or furnishing electrical power, 70 and if the periphery of the commutator becomes scratched or abraded, as mentioned, uniformity in the flow of the electrical current will not be uniform.

If the commutator be moved axially by 75 mechanical devices, the vibrations of such devices will be communicated to the commutator to a greater or lesser extent, with the result that its peripheral surface will become grooved and scratched. The principal 80 object of the present invention is to provide means for a longitudinal reciprocation of the commutator and shaft during the rotation thereof, which will not be attended with vibration, or at least will be accompanied 85 with less vibration than by other means.

Referring to the drawing, there is illustrated a generator provided with a horizontal shaft 1 which may be rotated by any suitable means, a part of its bearings being 90 indicated at 6 supported by a shaft-housing 24. A commutator 5 is mounted upon and is movable with the shaft; and at 4 is indicated the armature for the generator, which, together with the coils 3, are preferably disposed within a suitable housing 2.

A suitable base 7 is employed for housing the lower part of the commutator, and by means of keepers 10 the metallic brushes 9 are secured to the brush holders 8, said 100 brush holders, as best shown in Fig. 1, being secured upon the base or support 7, so that the terminal parts *a* of the brushes may engage the periphery of the commutator.

It will be understood that, while the bearings for the shaft permit rotation, said bearings, parts of which are best shown in Fig. 2, also permit longitudinal movements of said shaft. Also, it is well known that on account of electrical attraction between an 110

armature and the adjacent coils, during the rotation of said armature, there will be a tendency for the armature to remain within the magnetic field of the coils,—thus, if the shaft, while rotating, together with the armature and commutator be moved longitudinally a limited distance in the direction indicated by the arrow 11, and then released, the parts will return to their former positions, with the armature disposed normally or within the field of attraction, the shaft sliding in its bearings.

Means are provided and will be described for causing the limited movements mentioned in a manner to be practically free from vibration. Secured by screws 34 upon the shaft housing 24 (Figs. 2, 3.) is an apertured insulating disk 22 upon which are mounted by any suitable means, a plurality of electromagnets. They are shown in said Figs. 2 and 3 with closed circuits, their cores 50 traversing the disk 22, while disposed adjacent to the end of the shaft, substantially equi distant from each other and parallel with and equi distant from the axis of the shaft.

Secured by screws 25 upon the outer end of the cores of the electromagnets and disposed substantially parallel with disk 22 and secured by bolts 26 and 27 to the first disk is a second insulating disk 23. Traversing a central aperture of disk 22 and disposed axially of and threaded in the end of the shaft is a spindle 14 which carries an insulated finger 15, said finger being disposed in a central aperture of disk 23 with its axis in alinement with the axis of the spindle.

Upon disk 23 are mounted all of the electrical circuit making and breaking means. Secured upon this disk by the binding screw 32 is a metallic bracket 35 which also operates as an electrical conductor, said bracket being provided with a post 56, and at its free end it is provided with a buffer or stop-pin 55 which is threaded therein.

Mounted upon bracket 35 and adapted to have a limited swinging movement, is a link 17 which is of electromagnetic material and for convenience of description is designated as a first electrical conductor. It is provided with a set screw 20 disposed in line with the spindle and finger 15; and upon this link are mounted the electrical contact-screw 19 and a post 57. Numeral 21 indicates a spring having its respective ends mounted upon the posts 56 and 57, tending to normally cause an outward swinging movement of the link 17, said movement, however, being limited by the stop member 55.

Secured upon the disk 23 by means of the binding post 53, is an electrical conductor formed as a supporting-plate or arm 48, upon which, by means of a keeper 51, is

mounted a resilient strip 16 which for convenience of description is designated as a second electrical conductor, a suitable insulating plate 49 being interposed between the conductors 48 and 16. It will be seen 70 hereinafter that the keeper 51 also operates as an electrical conductor.

Numeral 18 indicates an electrical conductor or screw in communication with a plate or arm 48 and which conductor is threaded into the strip 16, as best shown in Fig. 3, the lower end of said conductor engaging a button 47 preferably constructed of platinum, carried by the plate 48.

Numeral 39 indicates a metallic plate operating as an electrical conductor, provided with a button 38 disposed adjacent to the screw 19 and preferably constructed of platinum, said plate 39 being secured to the disk 23, by the binding screw 40.

It will be understood that when the circuit for the electromagnets are closed as shown in Figs. 2 and 3, the adjacent shaft will be attracted thereto and will move longitudinally in the direction indicated by the arrow 11, while rotating, until the end thereof engages the cores of the electromagnets, the finger 15 moving through the space b, the commutator thereby moving transversely of the brushes so that the wear upon its periphery will be substantially uniform.

When the electrical circuit for the electromagnets is broken, the shaft, while rotating, will gradually move longitudinally in a reverse direction to that described, on account of the attraction between the armature and coils 3, said circuit being broken by the swinging movement of the resilient conductor 16 which engages the finger 15, the swinging movement of the conductor 16 causing a corresponding movement of the link 17. In order that the link 17 may move practically without vibration, the bracket 35 is provided, as best shown in Fig. 4, with opposed arms 59 each having an ear 60 in 110 which is respectively threaded the pins 36 and 37, adapted to be disposed in alinement and bearing upon opposed parts of the link, near its terminal, to provide its pivotal mounting.

Having described the principal parts employed for making and breaking the electrical circuits for the electromagnets, the automatic operation of said parts will be readily understood.

Electrical energy may be derived from any suitable source, as a battery 28. The battery is provided with a conductor 29 connected with a binding post 30, and an electrical conductor 31 connects the post 30 with the electromagnets 12, as best shown in Fig. 5. The return current from the electromagnets is through the electrical conductor 33 to the binding post or screw 32 and thence to the electrical contact screw 19 130

and, in succession, through link 17, bracket 35 and the threaded pivot-pins 36 and 37.

The current being conducted to the point of contact-screw 19, is conducted therefrom 5 to the platinum button 38 which is a part of the conductor 39, and therefrom is conducted to the binding screw 40, and through the conductor 42 the current passes to binding post 41.

10 A fuse 43 is interposed between the binding posts 41 and 44 and the current passes therethrough to the binding post 45 by means of conductor 46, and from the binding post 45 the current passes to the battery

15 through the conductor 47^a to complete the circuit, said circuit being for the purpose of energizing the electromagnets for moving the shaft in the direction indicated by the arrow 11.

20 Upon the completion of the longitudinal movement of the rotating shaft, the finger 15 of the spindle 14 will automatically cause the circuit to be broken, and the spring 21 will operate to normally cause the circuit 25 to remain broken and thereby permitting a longitudinal movement of the shaft toward the coils.

When the last named movement of the shaft is complete, so that the armature is 30 disposed in the position shown in Fig. 1, the finger 15 and spindle 14 being moved inwardly, the point of the conductor or screw 18 will engage the platinum button 47 since the conductor 16 is resilient, and 35 thereupon an electrical circuit will be established through the conductor 48, the insulation plate 49 permitting a circuit to be established only through the point of screw 18 and the platinum button 47 at required intervals.

40 This last described circuit is established from the battery through the electromagnets to the binding post 32, the same as already described. From the binding screw 32 the current is conducted to the keeper 51 through 45 conductor 52, the screw or keeper 51 being in electrical contact with the resilient conductor 16 and insulated from the supporting-plate or conductor 48. The current is 50 conducted to the point of screw 18 and thence to the binding post 53 through the platinum button 47 and conductor 48. From the binding post 53 the current is conducted to the binding screw 40 by the conductor 55 54, and from the binding screw 40 the current is conducted to the battery through the fuse 43 and the conductors 46 and 47.

55 This last electrical circuit is established when the shaft has completed its longitudinal movement and is disposed in the position shown in Fig. 1 of the drawing. The circuit being completed, the electromagnets will be energized by the battery, and the link will swing inwardly against the force 60 of spring 21, said link being disposed ad-

jacent to the screws or keepers 25, said screws 25 being in engagement with and serving as continuations of the cores 50 of the electromagnets. In operation, on account of the attraction between the link 17 70 and the cores of the electromagnets, the link will readily swing on its pivotal mounting toward the disk 23. This movement of the link causes the contact screw 19 to engage the platinum button 38 of the metallic plate 75 39 and establishes the electrical circuit, and this circuit will be maintained during the longitudinal movement of the shaft indicated by the arrow 11.

The movement of the shaft last mentioned will be continued until the finger 15 engages the set-screw 20, as already described, for breaking the circuit, and since the spring 21 will maintain the contact-screw 19 disengaged from the platinum button 38, the circuit will remain broken during the return movement of the shaft to the position shown in Fig. 1. By means of the devices thus described the shaft, during its rotation will be reciprocated longitudinally, the operation being automatic and practically free from vibration, this feature being of importance and one of the advantages to be derived, other advantages of the invention being features relating to durability and economy of manufacture of the parts for effecting the movements mentioned for the shaft and the commutator carried thereby.

55 The link 17 is disposed within the field of attraction of the electromagnets at all times when the latter are energized. The limited 100 arc of movement for the link, caused by the spring 21 when the electrical circuit is broken, may be regulated by the set-screw or 105 stop 55. Numeral 58 (Fig. 1.) indicates a hood preferably used for housing the electromagnets and their connections.

While I have shown and described a plurality of electromagnets, a lesser or greater 110 number or a single electromagnet may be employed, and I do not wish to be understood as limiting myself in this respect, nor to the number or arrangement of electrical conductors, nor to form, size or proportion 115 of parts, nor to minor details of construction, since the scope of the invention is determined by the claims.

I claim:

1. In combination with the shaft, armature and the coils of an electric generator, said shaft being journaled to permit longitudinal movements and the armature being normally maintained in the plane of the coils, an electromagnet positioned adjacent to an 120 end of said shaft, an electrical conductor, a source of electric supply in communication with the conductor designated herein as the first electrical conductor to energize the electromagnet for moving the shaft longitudi- 125 130

nally, an actuating member movable by the longitudinal movement of the shaft for terminating the communication of said conductor with said source of electric supply, a second electrical conductor designated herein as the second electric conductor in communication with the electromagnet, and means to establish a connection between the second conductor and the source of electric supply after the communication of the first named conductor with said source of electric supply has been terminated.

2. In combination with the shaft, armature and coils of an electric generator, said shaft being journaled to permit longitudinal movements, an electromagnet positioned adjacent to an end of said shaft, a link, designated herein as the first electric conductor, a source of electric supply in communication with said link or conductor to energize the electromagnet for moving the shaft longitudinally, an actuating member movable by the longitudinal movement of the shaft while interposed between the link and shaft for terminating the communication of the link with said source of electric supply to permit a reverse longitudinal movement of the shaft by operation of the coils, a metallic strip in communication with the electromagnet, and means to establish a circuit between the metallic strip and the

source of electric supply after the electrical communication of the link with said source of electric supply has been terminated and after the shaft has performed its reverse longitudinal movement.

3. In combination with the shaft, armature and coils of an electric generator, said shaft being journaled to permit longitudinal movements, an electromagnet positioned adjacent to an end of said shaft, a pivotally mounted link, a source of electric supply in communication with the link to energize the electromagnet for moving the shaft longitudinally, an actuating member movable by the longitudinal movement of the shaft for terminating the communication of the link with said source of electric supply to permit a reverse longitudinal movement of the shaft by operation of the coils, a resilient strip having a metallic connection with the electromagnet, and means to establish a connection between the metallic strip and the source of electric supply after the shaft has performed its reverse longitudinal movement.

In testimony whereof, I have affixed my signature in presence of two witnesses.

ELBERT R. O'KEEFFE.
